UNITED STATES PATENT OFFICE.

SETH L. ISHAM, OF ST. PAUL, MINNESOTA; ANNA M. ISHAM ADMINISTRATRIX OF SAID
SETH L. ISHAM, DECEASED.

COLLAR.

No. 899,167.

Specification of Letters Patent.

Patented Sept. 22, 1908.

Application filed July 23, 1907. Serial No. 385,211.

To all whom it may concern:

Be it known that I, SETH L. ISHAM, a citizen of the United States of America, and a resident of St. Paul, in the county of Ramsey and State of Minnesota, have invented 5 certain new and useful Improvements in Collars, of which the following is a specification.

My invention relates to improvements in 10 collars and more particularly to that class commonly termed horse collars. Among its objects are to provide means on the rim roll for preventing the hame from slipping out of place and for reinforcing the strength of the 15 rim roll. Another object is to protect the seam between the outer edges of the back roll so as to prevent cutting of the seam fastenings by friction while the collar is in use, thus materially increasing its durability and 20 usefulness.

In the accompanying drawings forming 25 part of this specification, Figure 1 is a view in perspective of the face of my improved horse collar; Fig. 2 is a view in perspective of the back of the horse collar; Fig. 3 is a cross section of my improved horse collar on the line X—X of Fig. 1; Fig. 4 is a detail perspective view of the protecting element of 30 the seam fastenings of the back roll; and Figs. 5, 6, and 7 are detail cross sectional views of the rim roll showing alternate means for holding the hame in the bed between the rim and back rolls of the collar.

In the drawings A represents the rim roll 35 and B the back roll of a horse collar. These rolls are provided with the usual filling material 2 such as straw and are formed with a hame bed C in the usual manner by stitching or otherwise fastening at 3 the pieces of 40 leather 4, 5, and 6 together. Immediately adjoining the hame bed C on the rim roll a longitudinal ridge or detent D is formed by creasing the piece of leather 4 and whip sewing a thong 7 of raw hide or cord of suitable 45 material throughout the length of said ridge. This ridge as constructed is adapted to assist in holding the hame in its bed C on the collar and prevents the hame from slipping out. The thong or cord 7 protects the surface of the ridge from wearing and abrasion and with the ridge reinforces the strength of the rim roll. The ridge D can be constructed in various ways within the spirit of my invention. In Fig. 5 it is formed by chain stitching 50 a thread at 8 through the laps of the

ridge D. In Fig. 6 the laps of the ridge D are fastened together by rivets 9 and in Fig. 7 the thong 10 of raw hide is chain stitched through the laps of the ridge D instead of being whipped around the ridge as illustrated 60 in the preferred construction.

The back roll of the collar is provided with a face lining E of felt or other suitable material which lining has an edge 11 projecting out of the back roll between the outer edges of its leather walls 12 and 13. The lining E is provided with projecting points 14 along its outer edge and the laps of the stitching 15 pass through interstices 16 between these points in forming the seam between the outer edges 12 and 13 of the back roll. The points 14 protect the seam of the back roll against cutting and abrasion of the seam fastenings by friction while the collar is in use. The stitching 15 is preferably made by whip sewing a raw hide thong or other suitable cord through the edges of the walls of leather forming the back roll, the inner laps of said thong passing through the body of the lining E and the outer laps passing through the interstices 16 between the points 14 of the projecting edge of said lining. 70 75 80

In accordance with the patent statutes, I have described the principle of operation of my invention, together with the construction 85 which I now consider to represent the best embodiment thereof, but I desire to have it understood that the apparatus shown is only illustrative and that the invention can be carried out by other means and applied to 90 uses other than those above set forth, within the scope of the following claims.

Having described my invention, what I claim as new and desire to protect by Letters Patent, is:—

1. A horse collar provided at the outer seam of its large roll with a series of points projecting out of said seam and secured directly therein between the outer edge of the collar back and the outer edge of the collar face, said points projecting from between the fastenings constituting the seam, for the purposes specified. 95 100

2. A horse collar provided with a lining of suitable material between the collar back and collar face of the back roll, said lining projecting from within said back roll and between the edges of the collar face and collar back, the projecting edge of said lining having a series of points and a cord of raw hide 105 110

or other suitable material whip sewed through the outer edges of the collar back and collar face and said lining, the outer laps of said cords passing between the interstices of said 5 points, for the purposes specified.

3. In a collar of the class set forth, a seam formed between the front face and back face of one of its rolls, said seam constituting the outer edges of the faces of said roll, a series of 10 points projecting from between said edges, and fastenings passing through said edges and the interstices between said points, for the purposes specified.

4. In a collar of the class set forth, a seam

formed between the front and back faces of 15 one of its rolls having fastenings passing through the outer edges of the laps of said seam, and a series of protecting points projecting out of said seam from between said fastenings, for the purposes specified.

In testimony whereof, I have signed my name to this specification, in the presence of two subscribing witnesses.

SETH L. ISHAM.
